UNITED STATES PATENT OFFICE.

MARY L. SHERIN, OF NEW YORK, N. Y., ASSIGNOR TO THE WARREN FEATHER-BONE COMPANY, OF THREE OAKS, MICHIGAN.

DESIGN FOR A GIRDLE.

SPECIFICATION forming part of Design No. 34,050, dated February 5, 1901.

Application filed December 29, 1900. Serial No. 41,536. Term of patent 14 years.

To all whom it may concern:

Be it known that I, MARY L. SHERIN, a citizen of the United States, residing at the city of New York, in the county of New York and State of New York, have invented and produced a certain new and original Design for a Girdle, of which the following is a specification.

This invention relates to a design for a girdle.

The design is fully illustrated in the accompanying drawings, forming a part of this specification, in which—

Figure 1 is a plan view of a girdle embodying the features of my design when extended or spread out flat. Fig. 2 is a front perspective view of a girdle embodying the features of my design.

As shown in the drawings, the leading or material features of my design consist of the

bands A A' A'', and groups of cross-ribs B. The bands A A'' are slightly larger than the band A', which gives the girdle a slightly-flaring shape. Extending diagonally across the group of cross-stays B at each end of the girdle are the stays C. At each end of the girdle are pieces or stays D. The stays D are provided at suitable intervals with eyelets.

Having thus described my invention, what I claim as new, and desire to secure by Letters Patent, is—

The design for a girdle, as herein shown and described.

In witness whereof I have hereunto set my hand and seal in the presence of two witnesses. 35

MARY L. SHERIN. [L. s.]
